UNITED STATES PATENT OFFICE.

KARL BERGSKAUG, OF BROOKLYN, NEW YORK.

PACKING-TOOL.

1,393,605.

Specification of Letters Patent.

Patented Oct. 11, 1921.

Application filed February 9, 1921. Serial No. 443,732.

To all whom it may concern:

Be it known that I, KARL BERGSKAUG, a citizen of the United States, and resident of the city of New York, borough of Brooklyn, in the county of Kings and State of New York, have invented a new and Improved Packing-Tool, of which the following is a full, clear, and exact description.

My invention relates to a packing tool and aims to provide a device of this character more particularly adapted for use in connection with the packing of tubes.

With regards to condenser tubes, it is a well appreciated fact that considerable difficulty has been experienced in applying the packing associated with the heads of the tubes and the ends applied thereto, in that it has been necessary to utilize great care in applying the packing material.

For this purpose a tool has also been employed, which has been, to say the least highly inefficient in that constant care is necessary to properly complete the operation.

From the foregoing it will be seen that in connection with this class of work, it is necessary to employ a mechanic skilled in the application of packing, thus increasing the expense of this operation, aside from the fact that a skilled worker is incapable of packing more than an extremely limited amount of tubes within the course of a day's work.

Aside from this, it is also well known by those conversant with the operation referred to, that even with the best of care, tubes must be frequently readjusted; and that also even a skilled mechanic will very often improperly perform the operation, necessitating this being again resorted to, thus delaying the work and adding to the expense.

Having these and other defects in mind, I have now constructed a packing tool, which primarily shall be simple in construction, and may be operated by relatively unskilled labor, which packing tool is primarily intended for use in connection with the application of packing material to the ends of tubes, and heads applied thereto although not necessarily limited to this adaptation.

Another object of my invention is the pro-

vision of a tool of the character stated, by means of which the tube will be evenly and correctly packed, so that it will not be necessary to resort to duplicate work to insure proper packing.

Another object of my invention is the construction of a tool in which a far greater amount of packings may be accomplished than has heretofore been possible, thus reducing the expense of this operation to a minimum.

Further objects of my invention will appear in the annexed specification and drawings which latter present one practical embodiment of my invention, and in which—

Figure 1 is a plan of a tool embodying my improved construction.

Fig. 2 is a side view thereof.

Fig. 3 is a sectional side view showing my tool in its initial position with respect to a tube and head to be packed.

Fig. 4 is a sectional end view taken along the line 4—4 in the direction of the arrows in Fig. 6.

Fig. 5 is a sectional view taken through the body of the tool along the line 5—5 and in the direction of the arrows indicated in Fig. 3.

Fig. 6 is a partly sectional view of the 80 position which the parts assume upon their initial application to a tube and head.

Fig. 7 is a view similar to Fig. 6 but showing the second stage of the operation.

Fig. 8 illustrates the third stage of the 85 operation accomplished.

Fig. 9 shows the essential elements in the position they assume when the packing operation has been practically completed, and

Figs. 10 and 11 are perspective views of 90 the main elements of the tool.

In these views the reference numeral 15 indicates the tube to be packed, to which the head 16 is applied, including a body portion presenting screw threads 17, and having, in 95 the usual manner, an annular recessed part 18 extending below and forming a continuation of the screw threaded portion 17, it being noted that the packing is to be applied to the recessed portion.

It will primarily be seen that by means of my improved packing tool, it will not be

necessary to employ an expensive form of packing, strip material 19 being utilized for this purpose.

Also, reference being had to Fig. 1, it will be seen that the tool includes in its essential elements, a stem 20, handle 21, and a sleeve 22, surrounding the lower end of the handle.

With regard to the detailed construction, it will be noted, reference being had to Fig. 10 3, that the handle 21 is of a diameter sufficient to permit of its inner end being introduced into the sleeve 22 and it is to be noted that shoulders 23, forming a part of both the handle and sleeve serve to force these 15 two elements in opposite directions by means of a spring 24 interposed therebetween.

It will also be seen that the stem 20 is preferably formed with a shoulder 25 normally lying in a plane beyond the outer 20 edge of the sleeve 22, it being noted that the body of the stem 20, comprising an enlarged portion 26 is slidably mounted within the handle 21 and presents annular grooves 27 adjacent the outer end of the sleeve 22 25 for a purpose hereinafter more fully specified.

It will also be noted that a screw or other suitable element 28 co-operates with the longitudinally extending slot 29 forming a part 30 of the sleeve 22, this element engaging the inner end of the handle 21 and extending beyond the same to within one of the grooves 27. Thus all of the parts are permitted to move with respect to each other within certain limits, and it is to be noted that the 35 stem 20, sleeve 22 and the handle 21 may be secured in fixed relationship one with respect to each other by means of a movable latch 30 pivotally secured as at 31 to the 40 sleeve 22, and being capable of extending to an opening 32 formed in the handle 21 to project into the secondary groove 27.

In operation it will be noted that, as has been indicated in Fig. 6, a strip of packing 45 material 19 is brought to a position at which one of its ends will rest within the notch 33 forming a part of the sleeve 22, the body of said packing material passing around the stem 15 and through the notch 34. The operator now inserts the stem 20 into the tube 50 15 and upon exerting an inward control, subsequent to the release of the latch 30 which is now swung as in Fig. 6, to act as a guiding element for the material 19, the 55 shoulder 25 of the stem 20 will contact with the outer edge of the tube 15 and result in a movement of this element with respect to both the stem and sleeve 22 against the action of the spring 24 and this latter movement 60 will result in a projection of the packing material 19 from the position indicated in Fig. 6, to that illustrated in Fig. 7, i. e. into the recess 18.

In this connection it is to be noted, as 65 has been illustrated in Fig. 6, that the outer

edge of the sleeve 22 will contact with the head 16, and this together with the seating established between the tube 15 and shoulder 25 of the stem 20 will insure a firm co-operation of the parts one with the other.

A maintenance of the pressure exerted upon the handle 21 and a simultaneous rotation of the same will cause the packing material to be disposed in the manner illustrated in Fig. 8, and it will be noted that any damage to this material incident to the sharp edges of the various parts will be obviated, reference being had to Figs. 9 and 11, by means of the curved lateral edge 35 of the slot 36, forming part of the handle 80 21, which slot accommodates a portion of the packing material 19 when the parts are in the positions illustrated in Figs. 7, 8 and 9.

From the foregoing it will be appreciated that I have constructed a packing tool, particularly intended for use in connection with condenser tubes, but as aforesaid not necessarily limited to this class of work, which tool will be extremely simple in construction, and by means of which an unskilled operator will be capable of effecting a packing of a greater number of tubes, aside from the fact that each packing operation will be perfect in all details, it being noted that, as has been illustrated in Fig. 8, the end of the packing material 19 will be fed through into the recesses 18 so that even a severance of the material, subsequent to its application to the tool is avoided.

It will further be appreciated that numerous modifications of structure might readily be resorted to without in the least departing from the spirit of my invention, which I claim as—

1. A packing tool, including a stem, sleeve and handle, and means carried by said sleeve and adapted to co-act with said handle for normally forcing said sleeve and handle in opposite directions with respect to each other.

2. A packing tool, including a stem, handle and sleeve, said sleeve partially inclosing said handle and stem, shoulders forming a part of said sleeve and handle, and a spring introduced between said shoulders.

3. A packing tool, including a stem, sleeve and handle, said handle inclosing a portion of said stem, and means carried by said handle and extending into a groove forming a part of said stem for limiting the movement of said stem with respect to said handle.

4. A packing tool, including a stem, sleeve and handle, said handle inclosing a portion of said stem, and means carried by said handle and extending through and into a slot, and groove forming parts of said sleeve and stem respectively.

5. A packing tool, including stem, sleeve

- and handle movable with respect to each other, and a latch movably secured to said sleeve and being adapted when the parts are in locked position with respect to each other, 5 to extend into a groove forming a part of said stem through a slot in said handle.
6. A packing tool, including a sleeve, handle and stem, said sleeve presenting notches in its outer edge, said handle being formed 10 with a slot in its outer end and adjacent said notches.
7. A packing tool including a sleeve, handle and stem movable with respect to each other, said sleeve being formed with a reduced portion in its inner face, said handle being formed with a shoulder, a spring arranged within the reduced portion of said sleeve, and having one of its ends bearing 15 against the shoulder of said handle, its opposite end bearing against the inner end of the reduced portion whereby to normally tend to force said handle in a direction opposite to the tendency imparted to said sleeve, and means for limiting said movement.
- 20 8. A packing tool including a handle, sleeve and stem, said handle being formed with a slot in its outer end and being par-
- tially arranged within said sleeve, said stem being disposed within said handle and extending beyond the same, one of the side edges of said slot being curved adjacent its outer end. 30
9. A packing tool including a handle, sleeve and stem, said handle being formed with a slot in its outer end and being partially arranged within said sleeve, said stem being disposed within said handle and extending beyond the same, said sleeve being formed with a plurality of notches adjacent 35 its outer edge and at substantially diametrically opposite points therein.
10. A packing tool including a stem, sleeve and handle movable with respect to each other, and a latch member movably secured 40 to said sleeve and being adapted to lock the parts with respect to each other by being brought to extend into a groove forming a part of said stem through a slot in said handle, said sleeve and handle being formed 45 with means adapted to co-act with a strip of material to be packed, said latch being adapted to be swung from its disengaged position to a position at which it may act as a guide for said sheet of material.

KARL BERGSKAUG.
